UNITED STATES PATENT OFFICE.

ELI HOGAN, OF PORTLAND, OREGON.

COMBINATION-TOOL.

No. 807,382.

Specification of Letters Patent.

Patented Dec. 12, 1905.

Application filed June 12, 1905. Serial No. 264,953.

To all whom it may concern:

Be it known that I, ELI HOGAN, a citizen of the United States, and a resident of Portland, in the county of Multnomah and State of Oregon, have made certain new and useful Improvements in Combination-Tools, of which the following is a specification.

My invention is an improvement in combination-tools; and it consists in certain novel 10 constructions and combinations of parts hereinafter described and claimed.

Referring to the drawings forming a part hereof, Figure 1 is a perspective view of my invention. Fig. 2 is a plan view thereof. 15 Fig. 3 is a vertical longitudinal section. Fig. 4 is a diagrammatic plan view of the arrangement of the lines and circles on the inner dome, and Fig. 5 is a similar view from the front.

20 In the practical application of my invention I provide a base A of suitable material and of rectangular form having therein a central circular recess a and on the bottom thereof countersunk recesses a' for receiving the heads 25 of leveling-screws a'', passing upward through the base and engaging the lower surface of a circular metallic plate a'', seated within the recess. A rubber gasket a''' rests upon the plate and a hollow inner dome B upon the 30 gasket.

The inner dome B is provided with a circumferential flange b, fitting closely within the circular recess, and with a circumferential groove b' immediately above the flange. A 35 gasket-ring b'' is fitted around the dome upon the flange and supports a flange b''' of an outer transparent dome b''. The outer dome b''' is provided on its inner face adjacent to the shoulder with a circumferential groove b'', registering with the circumferential groove on the convex face of the inner dome, and a perforation b'' extends from the concavity of the inner dome into the space between the domes 40 for a purpose to be hereinafter described.

45 Bolts b'', having heads fitting in countersunk openings b''' on the lower surface of the flange of the inner dome, and with nuts b'' in countersunk openings b'' on the upper surface of the flange on the outer dome, secure the domes 50 together. Screws b''', engaging perforations in the base and having heads b'''' engaging the upper surface of the shoulder of the outer dome, secure the domes in the recess.

Upon the convex surface of the inner dome, 55 which is ground to a perfect spherical surface, I provide indicating-lines C, comprising a

base-line c, a major meridian c', and a minor meridian c''. Each of these lines is provided with a series of tangentially - arranged circles c'', the lines forming the diameters of the circles, 60 the diameter of each circle being equal to nine degrees of the base-line or meridian, and the circles bear numerals above their diameters from "0" to "9" and below their diameters from "0" to "90." The circles bearing 65 the numeral "0" are at the apex of the dome and at the junction of the major meridian with the base-line, while the circles bearing the numerals "9" and "90" are at the junctions of the minor meridian with the base-line. 70 Lines c'', parallel with the base-line, cut the centers of the circles on the major and minor meridians, and meridians c'' cut the center of the circles on the base-line and at the apex.

Graduated sights D D', the former provided 75 with cross-wires and the latter with a perforated disk, are slidably mounted in countersunk brackets d d' at the front and rear of the base to one side of the dome. A compass E is mounted in an opening e in the base in 80 front of the dome and is provided with a sliding shield e' for covering the same when not in use, and a scale F is secured to the upper face of the base at the rear of the domes.

For the protection of the domes a shield G 85 is provided comprising the ring g, having the flange g' fitting in the countersunk recess g'' in the upper face of the base and the spherical segments g'', separated by intervals g'', which are intended to register with the major and 90 minor meridians. A plate-spring g'', secured to the base, rests upon one side of the cap-flange, and a screw g'', having a mutilated head, engages the opposite side of the flange to retain the cap in place. 95

In assembling my device the domes are secured together and sealed, and a spirit or other liquid is introduced through the perforations b'' into the space between the domes, filling said space, with the exception of an air-bubble of nine degrees in diameter—that is, of a diameter corresponding to that of the tangential circles. The perforation is then sealed, and the domes are secured within the recess in the base, with the axis of the major 100 meridian in exact line with the longitudinal center of the base.

The operation of my device will be readily understood from the description. In surveying, for instance, the sights are raised, and 105 the base is leveled by means of the leveling-screws until the air-bubble coincides with the

circle at the apex of the dome. The base is then alined with the object, and the horizontal angle is obtained from the compass. To obtain the angle of inclination of an object, the dome should be level with respect to the base. The base is then placed flat on the inclined object, and the deviation of the bubble from the apex will be the angle of inclination. The angle of elevation of trees, buildings, or other objects may be obtained in a similar manner.

It will be evident from the description that my combination-tool is capable of many uses. It may be used as a level to level in all directions without moving the tool. The difference between low and high points in degrees may also be determined. The tool may be used as a plumb to plumb at any angle desired without moving the same and to determine the amount of angular deviation of objects. The tool may be used to level or plumb one way and any angle desired at right angles at the same time without moving the tool.

Having thus described my invention, what I claim as new, and desire to secure by Letters Patent, is—

1. In an apparatus of the character specified, the combination of a base provided with a central circular recess, a metallic disk in the recess, means for leveling the disk, a gasket on the disk, an inner dome on the gasket provided with a circumferential flange and a circumferential groove above the flange, a gasket-ring on the flange, an outer transparent dome provided with a flange resting on the gasket-ring and a circumferential groove, and fitting over and spaced apart from the inner dome, a liquid within the space between the domes, an air-bubble being provided, means within the grooves for sealing the domes, bolts for securing the domes together, the inner dome being provided with a graduated base-line on the convex face thereof, comprising four quadrants of ninety degrees, and a major meridian cutting the base-line, and with a series of tangential circles of nine degrees diameter arranged with their diameters on the base-line, and a major meridian, and bearing numerals above the line from 0 to 9 and below the line from 0 to 90, the circles bearing the numeral 0 being at the apex of the dome and at the junction of the base-line and meridians, and with a minor meridian at right angles to the major meridian, and provided with a series of tangential circles similarly arranged and numbered to the circles on the major meridian, and with lines parallel with the base-line and cutting the centers of the circles of the meridians, and with lines parallel with the meridians cutting the centers of the circles on the base-line, countersunk brackets at the front and rear of the base and in line with each other, graduated sights slidably mounted in the brackets, the front sight provided with cross-wires, and the rear sight with a perforated disk, a compass in an opening in the base and

in front of the domes, and a scale secured to the upper face of the base behind the dome.

2. In an apparatus of the character specified, the combination of a base provided with a central circular recess, a metallic disk in the recess, means for leveling the disk, a gasket on the disk, an inner dome on the gasket, an outer transparent dome fitting over and spaced apart from the inner dome, a liquid within the space between the domes, an air-bubble being provided, means for sealing the domes, means for securing the domes in the base, the inner dome being provided with a graduated base-line on the convex face thereof, and a major meridian cutting the base-line, and with a series of tangential circles of nine degrees diameter arranged with their diameters on the base-line and major meridian, and bearing numerals above the lines from 0 to 9, and below the lines from 0 to 90, the circles bearing the numeral 0 being at the apex of the dome and at the junctions of the base-line and meridian, and with a minor meridian at right angles to the said major meridian and provided with a series of tangential circles arranged and numbered similarly to the circles on the major meridian, and with a series of lines parallel with the base-line and cutting the centers of the circles on the meridians, and with a series of lines parallel with the meridian and cutting the centers of the circles on the base-line, movable sights at the front and rear of the base and in line with each other, a compass in front of the dome, and a scale at the rear of the dome on the upper surface of the base.

3. In an apparatus of the character described, the combination of a base, a metallic disk in a recess in the base, means for leveling the disk, a gasket on the disk, an inner dome on the gasket, an outer transparent dome fitting over and spaced apart from the inner dome, a liquid within the space between the domes, an air-bubble being provided, means for sealing the domes, the inner dome being provided with a graduated base-line on the convex face thereof, and a major meridian cutting the base-line, and with a series of tangential circles of nine degrees diameter, arranged with their diameters on the base-line and major meridian, and bearing numerals above the lines from 0 to 9, and below the lines from 0 to 90, the circles bearing the numeral 0 being at the apex of the dome, and at the junction of the base-line and meridian, and with a minor meridian at right angles to the said major meridian, and provided with a series of tangential circles numbered and arranged similarly to the circles on the major meridian, parallels and meridians cutting the centers of the circles on the major and minor meridians on the base-line respectively and a compass and a scale secured in the upper face of the base.

4. In an apparatus of the character de-

scribed, the combination of a base, a metallic disk within a recess in the base, means for leveling the disk, an inner dome resting on the disk, an outer transparent dome fitting over and spaced apart from the inner dome, a liquid within the space between the domes, an air-bubble being provided, the inner dome being provided with a graduated base-line on the convex face thereof and a major meridian cutting the base-line and with a series of tangential circles of nine degrees diameter, arranged with their diameters on the base-line and major meridian and bearing numerals above the lines from 0 to 9, and below the line from 0 to 90, the circles bearing the numeral 0 being at the apex of the dome, and at the junctions of the base-line and meridian; and with a minor meridian at right angles to the said major meridian, and provided with a series of tangential circles numbered and arranged similarly to the circles on the major meridian, and a compass and a scale secured to the upper surface of the base.

5. In an apparatus of the character described, the combination of a base, an inner dome resting within a recess in the base, an outer transparent dome fitting over and spaced apart from the inner dome, a liquid within the space between the domes, an air-bubble being provided, the inner dome being provided with a graduated base-line on the convex face thereof, and a major meridian cutting the base-line, and with a series of tangential circles of nine degrees diameter, arranged with their diameters on the base-line and major meridian, and bearing numerals above the line from 0 to 9, and below the line from 0 to 90, the circles bearing the numeral 0 being at the apex of the dome, and at the junction of the base-line and meridian, and with a minor meridian at right angles to said major meridian and provided with a series of tangential circles numbered and arranged similarly to the circles on the major meridian, and means for leveling the domes with respect to the base.

6. In an apparatus of the character described, the combination of a base, inner and outer domes resting on the base and spaced apart from each other, a liquid within the space between the domes, an air-bubble being provided, the inner dome being provided with a graduated base-line on the convex face thereof, a major meridian cutting the base-line, and with a series of tangential circles of nine degrees diameter, arranged with their diameters on the base-line and major meridian and bearing numerals above the lines from 0 to 9 and below the lines from 0 to 90, the circles bearing the numeral 0 being at the apex of the dome and at the junction of the base-line and meridian, and with a minor meridian at right angles to the said major meridian and provided with a series of tangential circles num-

bered and arranged similarly to the circles on the major meridian, means for sealing the domes, and means for leveling the domes with respect to the base.

7. In an apparatus of the character described the combination of a base, an inner and outer dome spaced apart and secured to the base, the inner dome being provided with a graduated base-line on the convex face thereof and a major meridian cutting the base-line and with a series of tangential circles of nine degrees diameter arranged with their diameters on the base-line and major meridian, and bearing numerals above the line from 0 to 9, and below the line from 0 to 90, the circles bearing the numeral 0 being at the apex of the dome, and at the junction of the base-line and meridian, and with a minor meridian at right angles to said major meridian, and provided with a series of tangential circles numbered and arranged similarly to the circles on the major meridian, a liquid within the space between the domes, an air-bubble being provided of a diameter equal to that of the circles, and adapted to coincide therewith, and means for leveling the domes with respect to the base.

8. In an apparatus of the character described the combination of a base, an inner and outer dome spaced apart and resting upon the base, the inner dome being provided with a graduated base-line on the convex face thereof, and a major meridian cutting the base-line, and with a series of tangential circles of nine degrees diameter, arranged with their diameters on the base-line and major meridian, and with a minor meridian at right angles to said major meridian, and provided with a series of tangential circles similarly arranged to the circles of the major meridian, a liquid within the space between the domes, an air-bubble being provided having a diameter corresponding to that of the diameter of the circles and means for leveling the domes with respect to the base.

9. In an apparatus of the character described, the combination of a base, inner and outer domes spaced apart and resting on the base, the inner dome being provided with a graduated base-line on the convex face thereof, and a major meridian cutting the base-line and with a minor meridian at right angles to said major meridian and with each of the lines provided with a series of tangential circles of nine degrees diameter, and arranged with their diameters on the lines, a liquid within the space between the domes, an air-bubble being provided of a diameter corresponding to that of the circles, and means for leveling the domes with respect to the base.

10. In an apparatus of the character described, the combination of a base, an inner and outer dome spaced apart and resting on the base, a liquid within the space between

the domes, an air-bubble being provided, the inner dome being provided with a graduated base-line on the convex face thereof, and major and minor meridians cutting the base-line and with a series of tangential circles of nine degrees diameter arranged with their centers on the lines and means for leveling the domes with respect to the base.

11. In an apparatus of the character described, the combination of a base, an inner and outer dome spaced apart and resting upon the base, the inner dome being provided with a graduated base-line on the convex face thereof and major and minor meridians cutting the base-line, a shield for the domes comprising a metallic cap, resting on the base, and provided with an opening at its apex and with radial openings corresponding to the major

and minor meridians of the dome, and means for removably securing the shield to the base. 20

12. In an apparatus of the character specified, the combination of an inner dome, an outer dome fitting over and spaced apart from the inner dome, the inner dome being provided with a graduated base-line on the convex face thereof and major and minor meridians cutting the base-line and with a series of tangential circles of nine degrees diameter arranged with their centers in the line and a liquid within the space between the domes, an 25 air-bubble being provided, and means for securing the domes together.
